Attest.

United States Patent Office.

JOHN LARIMORE AND J. M. WILLIAMS, OF CONNERSVILLE,
INDIANA.

Letters Patent No. 95,360, dated September 28, 1869.

IMPROVED RAILWAY-CAR COUPLING.

The Schedule referred to in these Letters Patent and making part of the same.

To all whom it may concern:

Be it known that we, JOHN LARIMORE and J. M. WILLIAMS, of Connersville, in the county of Fayette, and in the State of Indiana, have invented certain new and useful Improvements in Car-Coupling; and do hereby declare that the following is a full, clear, and exact description thereof, reference being had to the accompanying drawings, and to the letters of reference marked thereon, making a part of this specification.

The nature of our invention consists in the construction and general arrangement of the draw-head of a self-acting car-coupling, inside of which are two pivoted jaws, situated in proper position for the link to operate upon them, causing the pin to drop into the link, as will be fully shown hereafter; and, in order to enable others skilled in the art to which our invention appertains, to make and use the same, we will now proceed to describe its construction and operation, referring to the annexed drawings, in which—

Figure 1 is an upper inverted horizontal section.

Figure 2 is a longitudinal vertical section.

A represents the bumper of a railroad-car, in which are the pivoted jaws B B, with shoulders i i, which act as rests for the coupling-bolt C, while said bolt is up.

The jaws B B are pivoted, near the rear end, by pivots b b, the front ends of said jaws being forced inward by means of a spiral, rubber, or any other suitable spring, D, on each side, which springs press against the rear ends of the pivoted jaws.

These jaws can be used as sides of the bumper, and substituted for the permanent sides m m; but we prefer the latter, as they act as covers in keeping out rain, snow, dirt, &c., from the inside.

E is a stationary stop, against the rear end of which rest the springs D D.

The front end of said stop is forked, and has a rounded receptacle, in order to guide the link immediately under the coupling-bolt C, when inserted.

The coupling-bolt C is round, and has a projection, F, at its top, which extends so far down, that when inserted into the draw-head, it will rest upon the link H.

The coupling-bolt passes up through a slot in the top of the bumper, and passes up through a slotted tube, G, on the top of said bumper, which tube acts as a guide for the bolt.

Fitting over the tube G is a cap or cover, I, which can be removed, thus allowing the bolt to be detached from the bumper, when found necessary.

Connecting the cap or cover I with the coupling-bolt C is a chain, K, of suitable length, so as not to obstruct the pin when dropping into position.

In the bottom of bumper, and near the front end of stop E, is a slot, L, down through which the dirt, &c., which enters at the mouth of bumper, will pass.

When the coupling-link H is inserted in the bumper, it forces the shoulders i i, on the front ends of the jaws B B, open, or outward, which releases the coupling-bolt C, and allows it to drop down into the link, thus coupling the cars.

Having thus fully described our invention,

What we claim as new, and desire to secure by Letters Patent, is—

1. The bumper A, provided with pivoted jaws B B, having shoulders i i, constructed substantially as described, and for the purpose set forth.

2. The combination of the pivoted jaws B B, stop E, and springs D D, all substantially as and for the purpose set forth.

3. The stop E, constructed substantially as described, and for the purposes set forth.

4. In combination with the bumper A, the slotted tube G and cap I, substantially as and for the purpose set forth.

5. The combination of the bumper A, pivoted jaws B B, springs D D, coupling-bolt C, projection F, slotted tube G, and cap I, all constructed and operating substantially as and for the purposes herein set forth.

In testimony that we claim the foregoing, we have hereunto set our hands, this 9th day of July, 1869.

JOHN LARIMORE.

J. M. WILLIAMS.
